UNITED STATES PATENT OFFICE.

TORKEL O. HEGGEN, OF FORT DODGE, IOWA.

INTEREST-COMPUTING TIME-TABLE.

1,381,893.

Specification of Letters Patent. Patented June 14, 1921.

Application filed July 8, 1919. Serial No. 309,395.

To all whom it may concern:

Be it known that I, TORKEL O. HEGGEN, a citizen of the United States, and a resident of Fort Dodge, in the county of Webster and State of Iowa, have invented a certain new and useful Interest-Computing Time-Table, of which the following is a specification.

The object of my invention is to provide an interest computing time table of simple, durable and inexpensive construction, having means thereon for recording the number of expired and unexpired days of the year.

15 A further object is to provide such a device having members thereon for recording the number of expired days of the year, and for recording the number of unexpired days of the year, the members being of such material that the records made each day may be readily erased by the use of an ordinary rubber eraser.

20 A further object of my device is to provide means for recording the expired and unexpired days of the year, whereby the user may at a glance see the number of expired or unexpired days in the year, and means whereby the number of expired and unexpired days may be changed from day to day.

25 A further object is to provide such a device having parts so arranged that the user may find on one part of the device the number of unexpired days of the year, and may ascertain from another part of the device the number of expired days of the year.

30 A further object is to provide such a device having a cover comprised of hinged members, and having indicating characters representing the month of the year and the days of the month, and indicating characters representing the unexpired days of the year, and having similar indicating characters representing the expired days of the year.

35 With these and other objects in view my invention consists in the construction, arrangement and combination of the various parts of the device, whereby the objects contemplated are attained, as hereinafter more fully set forth, pointed out in my claims and illustrated in the accompanying drawings, in which:

40 Figure 1 shows a plan view of the device embodying my invention, showing the cover

members resting in their open position face upward.

Fig. 2 shows a transverse, sectional view of the device taken on the line 2—2 of Fig. 1.

60 Fig. 3 shows a transverse, sectional view taken on the line 3—3 of Fig. 1.

In the accompanying drawings I have used the reference characters A and B to indicate the cover members having the indicating characters thereon.

65 The cover members A and B are hinged together by means of a flexible binding 10. Resting on the flexible binding 10 is a stiff board or the like 11.

70 The stiff boards 11 are somewhat smaller than the flexible binding 10, so that the binding may be turned up at its edges and overlap the stiffening 11 at 12.

75 Resting on the cardboard 11 are the sheets 13 and 14. The sheet 13 has the expired days of the year listed thereon, and the sheet 14 has the number of unexpired days thereon.

80 Placed over the sheets 13 and 14 and of the same size as the sheets 13 and 14 are transparent protectors 15 and 16.

85 At the lower portion of the device are the openings 17 and 18 in the binding 10. Celuloid members 19 and 20 are placed therein. Over the celluloid member 19 is the word "Unexpired," and over the celluloid member 20 is the word "Expired." This indicates the side showing the unexpired and the side showing the expired days of the 90 year.

95 The indicating characters are separated by the vertical lines 21 and the horizontal lines 22.

The indicating characters are arranged so that at each side the day of the month is shown thereon, and at the upper and lower sides of the sheet are the names of the months of the year.

100 The indicating characters in the unexpired sheet starts with 365 on January 1st, and ends with 1 on December 31st of the same year.

105 The sheet containing the expired days commences with zero on January 1st, and ends with 364 on the 31st day of December of the same year.

110 It will be seen that when it is desired to compute the number of unexpired days at any certain date, all that is necessary for

the user to do is to glance at the upper portion of the sheet showing the names of the month and find the month which he desires to use, and then glance at the right or left of each sheet and find the day of the month that is to be used. Where the month column and the date column intersect will show the number of unexpired days in the year.

For example, if I were to figure the number of unexpired days from June 11th, it would be necessary to find the column containing June, and then glance at the right or left of the sheet showing the date and come to eleven. Where the June column and the eleven column intersect would show the number of unexpired days which, in this case, would be 204.

It will be seen that in computing discount it is desirable that the banker should know the exact number of days, and by my device he could readily ascertain the number of unexpired or expired days of the year.

The celluloid members 19 and 20 are provided so that the user of the device may record in pencil the number of unexpired and expired days upon said members. For example, if on June 11th, there were 204 unexpired days remaining in the year, the user would place upon the celluloid member 19 204 in pencil. This would be done at the commencement of business on June 11th, so that during the entire day if any notice of discount is to be computed, the user merely glances at the device and sees that under the unexpired heading on the celluloid member 19 there would be indicated the characters 204.

At the commencement of business on the following day, which would be June 12th, the user would erase the pencil characters 204 and place thereon the new characters 203 which would show the number of unexpired days on June 12th of that year.

On the opposite side of the cover member are the characters indicating the number of expired days. For example if it were necessary to compute the number of expired days from January 1st to September 12th, all that would be necessary would be to find the column headed by the month September, and then look at the right or the left of the sheet showing the date, and there find the numeral 12, and where the column containing 12 and the column containing September intersect, would show the number of expired days in that year, and in this case it would be 254.

For example at the commencement of business on June 11th, the number of unexpired days was 204 which would be recorded under the unexpired heading, and the user wanted to find the number of expired days, by the use of the process heretofore explained, on the expired sheet, it would show that on

June 11th, there had expired 161 days. The 161 is then recorded on the celluloid member 20 under the heading "expired."

It will be seen that the number of unexpired and expired days would always total 70 365, the number of days in the year.

If the user would want to compute any discount by the use of this device he could very readily compute the number of expired days or unexpired days and thereby calculate the notice of discount upon the note.

It will be seen that it is not exactly necessary to find the number of expired days from January 1st to a given certain date, but if it were desired to find the number of expired days between March 5th and July 9th, all that would be necessary would be to find the number of expired days on March 5, which would be 63, and then the number of expired days on July 9th, which would be 189. The difference between 189 and 63 would be 126 which would be the number of expired days between the given date March 5th, and July 9th.

The members 19 and 20 are preferably made of celluloid or may be made of any suitable material which will take pencil writing thereon and yet may readily be erased by using an ordinary pencil eraser.

It will be seen that the number of unexpired or expired days may readily be computed between any give dates of the same year or of different years.

This device is very handy: First that it can readily be used by anyone and will show the number of unexpired and expired days as recorded upon the members 19 and 20 each day, and yet enables the user to calculate the expired or unexpired days between any two given dates.

When the device is not in use, the covers A and B may be folded upon the hinged binding 10 forming a book.

The members 15 placed over the indicating sheets 13 and 14 protects the indicating characters from obliteration by usage.

By having the transparent members 15 the operator can use a pencil for following the column in which he desires to find a certain character and it will not leave a pencil mark upon the device.

Some changes may be made in the construction and arrangement of the parts of my device without departing from the essential spirit and purpose of my invention, and it is my intention to cover by my claim any modified forms of structure which may be reasonably included within their scope.

I claim as my invention:

An interest computing time table, comprising two adjacent sets of indicating characters, one, being provided with columns indicating the months of the year and with lines at right angles thereto indicating the

days of the month and with numerals arranged between said columns and lines for indicating the number of expired days in the year for any given month or day of 5 the year, the other being similarly provided with columns for indicating the months and lines for indicating the days and also being provided with figures indicating the number of unexpired days in a year for any 10 given date, substantially as set forth, and a

device adjacent to each of said sets of indicating characters capable of receiving pencil marks and also capable of having said marks erased without deterioration of said member, with the word "Expired" printed 15 adjacent to one of said devices and the word "Unexpired" adjacent to the other for the purposes stated.

Des Moines, Iowa, May 16, 1919.

TORKEL O. HEGGEN.
